UNITED STATES PATENT OFFICE.

ALBERT WEINGAERTNER, OF ST. LOUIS, MISSOURI, ASSIGNOR TO WEINGAERTNER MANUFACTURING COMPANY, OF ST. LOUIS, MISSOURI, A CORPORATION.

WINDOW-STOP ADJUSTER.

SPECIFICATION forming part of Letters Patent No. 783,766, dated February 28, 1905.

Application filed June 8, 1904. Serial No. 211,651.

To all whom it may concern:

Be it known that I, ALBERT WEINGAERTNER, a citizen of the United States, residing in the city of St. Louis, in the State of Missouri, have 5 invented certain new and useful Improvements in Window-Stop Adjusters, of which the following is a full, clear, and exact description, reference being had to the accompanying drawings, forming part of this specification.

My invention relates to an adjusting means for application to the stops of windows, through the medium of which said stops may be shifted laterally and secured to obtain the desired degree of close association between 5 the stop and the window-sash that rides thereagainst.

The invention consists in features of novelty hereinafter fully described, and pointed out in the claim.

Figure I is a vertical section through a window with the sash-stop shown applied thereto and held by a plurality of my adjusters. Fig. II is an enlarged horizontal section taken on line II II, Fig. I. Fig. III is a view, 5 partly in elevation and partly in longitudinal section, taken through portions of a window-frame and sash-stop applied thereto with one of my adjusters shown securing the stop to the frame. Fig. IV is a perspective view of the rear side of one of the washers of the adjuster.

1 designates one of the uprights of a window-frame, against which the upper and lower sashes 2 and 3 ride.

4 is an inner sash-stop that is fitted against the frame-upright 1 and which is provided at intervals with apertures 5. (See Figs. II and III.)

6 designates set-screws of smaller diameter than the diameters of the apertures 5, these 40 set-screws being inserted through said apertures and seated in the window-frame upright to hold the sash-stop thereto.

7 designates washers that are applied to the sash-stop at the location of the apertures 45 5. Each of these washers is furnished with a pair of tongues 8, integral with the body of the washer and projecting inwardly into the apertures 5. The tongues 8 are cut from the bodies of the washers, and a slot 9 is thereby 50 furnished in each washer, through which the shanks of the set-screws 6 are passed to extend to the window-frame upright. Each washer is so held by its tongues 8 that the slot 9 in the washer extends horizontally 55 across the sash-stop. This being true, it will be seen that when the set-screws 6 are loosened the sash-stop may be shifted inwardly or outwardly toward or away from the sash 60 against which it bears to secure the desired adjustment of said stop, after which upon the tightening of the set-screws the stop will be held securely in the adjusted position by reason of the bearing of the screw-heads against the bodies of the washers. 65

I claim as my invention—

As a new article of manufacture, a sash-stop adjuster consisting of a washer provided with a slot, tongues integral with said washer and extending from the body thereof at the 70 ends of its slot, and a set-screw passing through said slot, substantially as set forth.

ALBERT WEINGAERTNER.

In presence of—

NELLIE V. ALEXANDER,
BLANCHE HOGAN.
